UNITED STATES PATENT OFFICE.

BERTIE C. PARSONS, OF BOSTON, MASSACHUSETTS.

LOCKING MEANS FOR MOWING-MACHINE BLADES.

1,137,662.

Specification of Letters Patent. Patented Apr. 27, 1915.

Application filed July 25, 1914. Serial No. 353,028.

To all whom it may concern:

Be it known that I, BERTIE C. PARSONS, a citizen of the United States, residing at Boston, in the county of Suffolk and State 5 of Massachusetts, have invented an Improvement in Locking Means for Mowing-Machine Blades, of which the following is a specification.

This invention relates to mowing-machine 10 cutter-blades, and has for its object the provision of an improved form of locking means for the cutter-blades by which said blades are very securely held in place, and particularly against lateral strain, which 15 means admits of the ready removal and replacement of the blades, and avoids the employment of screws and bolts which are objectionable.

Figure 1 is a plan view of a portion of 20 a cutter-bar with blades secured thereto. Fig. 2 is a front elevation of the same. Fig. 3 is a vertical section through one of the plates showing the holding stud. Fig. 4 is a similar 25 sectional view, the locking-stud for the cutter-blade being withdrawn to permit of the removal of the blade. Fig. 5 is a detail in front elevation illustrating the deflection of the strip bearing the locking-stud.

The cutter-bar 10, has arranged upon it 30 at regular intervals headed-rivets 12, the heads of which are extended short distances above the face of the bar, to provide spaces between and beneath them to receive the shanks of the blades 14. The shanks of the 35 blades are made narrower than the cutting-portions thereof, incident to the formation of right angular recesses at the corners of the blank of which the blade is composed, and it is preferred that the widths of the 40 shanks shall be substantially equal to the distance between the headed-rivets, thereby to enable said shanks to fit snugly between the rivets and the blades to abut against each other, the heads of the rivets extending 45 over the edges or sides of the shanks for short distances. Arranged beneath the bar 10 is a long narrow strip 16 of steel, and said strip is riveted or otherwise secured to the bar, at regular intervals, to provide un- 50 attached portions therebetween, which portions are deflectable, and said strip has secured to its deflectable portions, at regular intervals, pins or studs 20, which are made long enough to extend through holes in the 55 bar 10, and also into or through holes in

the shanks of the blades. These studs, together with the headed-rivets aforesaid, hold the blades securely in place on the bar. It will be observed that the deflectable portions of the strip 16, are arranged opposite the shanks of the blades, so that the pins or studs will enter the holes in said shanks. Said unattached portions may be deflected sufficiently to withdraw the pins or studs far enough to admit of the removal of the 60 blades, and such deflection may be accomplished by projecting a pry between the strip and the bar, and herein recesses 25 are specially provided in the bar adjacent the unattached portions to receive a flat pry, 65 such for instance as the end-portion of a screw-driver 26, which may be thrust into any of the recesses and turned thereby to deflect the adjacent portion of the strip. On account of the inherent resiliency of the 70 strip its deflected portion or portions will resume its normal position when the pry is removed. This form of locking-means is simple, and can be easily and quickly operated, and does not involve the employment 75 of screws or bolts which are objectionable.

I claim:

1. A mowing machine cutter bar having headed elements secured thereto with the heads spaced from the blade receiving surface 85 of the bar, resilient strips secured to the opposing surface of the bar and provided at an intermediate point with a pin adapted for projection through an opening formed in the bar to project said pin beyond the plate 90 receiving surface of the bar, in combination with cutter blades having the shank portions reduced to a width approximately equaling the distance between the shanks of adjacent headed elements, the shanks of the cutter 95 blades being in part formed to bear against the pins of the elements throughout a portion of the rounded surfaces, each of said plates being formed with an opening to receive said pin.

2. A mowing machine cutter bar having headed elements secured thereto with the heads spaced from the blade receiving surface of the bar, resilient strips secured to the opposing surface of the bar and provided at an intermediate point with a pin adapted 105 for projection through an opening formed in the bar to project said pin beyond the plate receiving surface of the bar, in combination with cutter blades having the shank 110

portions reduced to a width approximately equaling the distance between the shanks of adjacent headed elements, the shanks of the cutterblades being in part formed to bear against the pins of the elements throughout a portion of the rounded surfaces, each of said plates being formed with an opening to receive said pin, that surface of the bar underlying the strip being formed with re-

cesses to permit the insertion of means for 10 operating the strip.

In testimony whereof, I have signed my name to this specification, in the presence of two subscribing witnesses.

BERTIE C. PARSONS.
